Elmer J. Ayer, of Lowell, Mass.
Ayer's New Lowell Manufacturing Company of Lowell,
Letters Patent No. 1176, dated Dec. 20, 1859.

2

Dec. 1176

The Schedule referred to in these Letters Patent and making part of the same.

To all whom it may concern:

Be it known that of Elmer J. Stev., of Lowell, in the County of Middlesex and State of Massachusetts, have originated and designed a new pattern for Carpets or other fabrics, of which the following is a full, clear and exact description, reference being had to the accompanying drawings making part of this Specification.

Corner A. is quarter of a figure composed of four shells, connected by a narrow band, surrounding a wreath of eight leaves, Corner B. is a quarter of an irregular figure supporting four plain leaves; in the center of said figure is an eight cornered block supporting a small cross.

C & D. are solid bars running parallel with each other throughout the design, one side of each being bordered by the miffles 1 and 2. Lying between the bars C & D. in the center of design is the Leaf E.

Underlying the before mentioned figures are bars F and G. composed of small diamonds. These bars by their connections form quarters of a cross in the corners F & G.

Lying between the crosses and bars C and D. are the Springs 5. The colors employed in the different portions of the design may be varied to suit the taste and wish of the manufacturer.

Claim

What I claim as my invention and desire to secure by Letters Patent, is the design or pattern for Carpets or other fabrics, herein set forth.
